UNITED STATES PATENT OFFICE.

DAVID E. ROSS, OF LA FAYETTE, INDIANA, ASSIGNOR TO ROSS GEAR & TOOL COMPANY, OF LA FAYETTE, INDIANA, A CORPORATION OF INDIANA.

MACHINE FOR MAKING HELICALLY-GROOVED ACTUATING MEMBERS FOR STEERING GEARS.

Application filed March 26, 1924. Serial No. 702,068.

This invention is a novel machine for use in the manufacture of steering gear actuating-members having varying helical grooves, of the character shown and described in my application for steering gear filed Sept. 5, 1922, Serial No. 586,145.

Such actuating members are each formed on or connected to the steering gear shaft and the helical groove therein is engaged 10 by an arm on the rocker shaft lying at right angles to the steering shaft; whereby when such an actuating member is turned on its axis the related rocker shaft is rocked with accelerating motion by the movement of the 15 arm from a position at the center of the length of such groove toward either end of the groove. Such helical groove has a pitch of approximately 90 degrees at the center of its length, (or point where the 20 steering shaft is in normal "straight ahead" running position of the gear) and progressively lessens in pitch from such center point toward each end thereof; such varying groove causing an increasingly accelerated 25 movement of the rocker shaft as the arm thereon moves from the position of engagement with the center of such groove toward either end thereof; as more fully explained in my aforesaid application.

The groove in such actuating member has to be made with exceeding nicety and accuracy; and the object of my present invention is to provide a machine whereby, after a blank for an actuating member has 35 been shaped to the proper size and form, such variable helical groove may be accurately cut therein.

I will explain the invention with reference to the accompanying drawings, which 40 illustrate one practical embodiment of the invention; and refer to the claims for the summaries of the essentials of the invention, and the novel combinations of parts, and novel features of construction, for all of 45 which protection is desired.

In said drawings:

Figure 1 is a top plan view of so much of the machine as is necessary to a full understanding of the invention.

Figure 2 is an enlarged front elevation of part of the mechanism shown in Fig. 1.

Figure 3 is a rear elevation of the parts shown in Fig. 2.

Figure 4 is an enlarged detail section on the line 4—4 of Fig. 7.

Figs. 5 and 5^a are enlarged perspective views of the connection between the master cam and its driving means.

Figure 6 is a sectional view on the line 6—6 Fig. 1.

Figure 7 is a sectional view on the line 7—7 Fig. 1.

Figure 8 is an enlarged view of the blank holding devices.

Figure 9 is a longitudinal section through Fig. 8.

Figure 10 is a detail sectional view on the line 10—10 Fig. 7.

The mechanism shown may be mounted on a support 1 of any suitable construction 70 such as the frame of an ordinary turning lathe. Upon this supporting frame is mounted a head stock 2, and a tail stock 12. Said stocks may be mounted upon rails 1^a of the supporting frame in any suitable way so as to be relatively adjustable toward or from each other, and may be firmly held in any adjusted position, by any suitable means. The head stock 2 carries a shaft 2^a which is provided with means hereinafter 80 described for engaging and supporting one end of a blank B from which the actuating member is made.

The shaft 2^a is preferably rotated as hereinafter explained so as to turn the blank B. 85 The tail stock 12 is provided with the usual manually adjustable center screw 12^a, and the actuating member blank B is centered between the head and tail stocks during the operation of cutting the groove preferably 90 as hereinafter explained.

Upon the frame 1 intermediate the head and tail stocks is mounted an adjustable supporting plate 18 on which is mounted (to slide longitudinally thereof) a frame 8 which is bodily adjustable backward or forward on the base plate 18. As shown in Figs. 2 and 3, slide 8 has longitudinally disposed dove-tail side members 8^e which engage oppositely disposed dove-tail guides 18^e on the base plate 18; and slide 8 has a nut, or internally threaded sleeve portion 8^f (Fig. 10) which is engaged by a screw shaft 18^f rotatably but longitudinally immovably supported in bearings 18^b on the 100 base plate 18. Said screw shaft 18^f is pro-

vided with a hand wheel 18^e by turning which slide 8 with the parts mounted thereon can be shifted bodily forward or backward on plate 18.

5 The slide 8 is provided at its ends with bearings 8^a and 8^x (Fig. 7) which are engaged by trunnions 9^e, 9^d on a rocking member 9^b, which carries the cutter shaft and which rocking member can tilt on said 10 trunnions, and is adapted to be bodily oscillated or rocked to the right or left, or laterally on said frame.

This rocking member 9^b has a longitudinal radial projection 9^a on its upper side in 15 which is journaled a spindle 10 which is rotatably but longitudinally immovably mounted on the rocking member 9^b, and carries on its front end a cutter 10^e and may have a thrust bearing 10^b, of any suitable 20 construction, on its rear end abutting against a stud 9^g on the rocker member 9^b, as shown.

The cutter 10^e is preferably a milling cutter. The spindle 10 may be rotated by 25 any suitable means. Preferably a pulley 10^d thereon is driven by a belt 10^x from a suitable overhead driving pulley (not shown).

This rocking member 9^b has a projection 9^a 30 on its rear end spaced from the pulley 10^d to permit the master cam C, hereinafter referred to, to lie between said projection 9^a and the end of said spindle 10. This master cam is securely held in position as herein- 35 after explained.

This master cam C has a variable helical cam groove *m* cut therein, (see Fig. 1) said cam groove *m* determining the shape of the helical groove cut in the actuating members 40 B. The groove *m* in the master cam C is engaged by a pin or plunger 11. This pin 11 is contained in the socket in a member 9^h on or rigidly attached to the part 9^a and pin 11 is preferably normally projected outwardly so as to properly engage the groove *m* in the master cam C by means of an adjusting screw 11^a (see Fig. 4), abutting against the inner end of the pin or plunger 11, so as to hold the pin always in close engagement with the groove *m* in the master cam and prevent any lost motion or chatter. 50

When the master cam C is rotated as hereinafter explained, it will cause the rocking member 9^h to swing or oscillate laterally on the frame 8, and thus cause the cutter 10^e to move through an arc lengthwise of the blank B. Preferably the master cam C and the blank B are positively rotated in unison by the following means:

60 On the spindle 2^a is a worm gear 2^b Figs. 1 and 6 which meshes with a worm 3^a on a shaft 3 which is journaled in bearings in the head stock 2. This shaft 3 extends at right angles to the spindle 2^a and its rear end is 65 journaled in bearings 8^e, 8^x on a bracket or

extension 8^z on or attached to the rear end of the slide 8.

A worm 3^b, splined on the rear end of shaft 3 meshes with a worm gear 7^a on a shaft 7 journaled in bearings on the extension 8^z as shown; and shaft 7 is coupled to a member 7^b which drives the master cam C as hereinafter explained.

On the shaft 3 intermediate the gears 3^a and 3^b is a spiral gear 3^c which meshes with a 75 spiral gear 4^c on a shaft 4 which lies at right angles to shaft 3 and is journaled in bearings on a bracket 5. This shaft 4 has a worm gear 4^a which meshes with a worm 6^a on a shaft 6 journaled in suitable bearings 80 attached to the bracket 5 to one side of, and below the shaft 3, and extending at right angles to the shaft 4, and parallel to shaft 3. Shaft 6 may be driven by any suitable means, As shown it has a stepped cone- 85 pulley 6^b which can be belted to any suitable driving pulley not shown.

By reason of the described worm or spiral gearing or other suitable gearing a great 90 reduction in speed and corresponding increase of torque is produced between the pulleys 6^b and the spindle 2^a, and between said pulley 6^b and the master cam drive shaft 7.

The shaft 7 lies at right angles to the 95 shaft 3 and parallel with and in rear of the shaft 4. This shaft 7 is adapted to drive the master cam C and is preferably operatively connected therewith as hereinafter described. The master cam C is preferably 100 made as described in my application for patent, filed March 26, 1924, Serial No. 702,067, and is in the form of a cylindrical body C Fig. 1 provided with axially disposed trunnions *m'* and *m''* at its opposite ends, and the body of this cam is provided with a varying helical groove *m*, as described in my said application, which groove conforms in pitch and contour with the groove to be formed in the actuating members B as herein- 105 after explained.

110 Preferably, the trunnions of the master cam are mounted in bearings 8^a, 8^b on the slide 8 so that the master cam when in position will lie between the rear end of the shaft 10 and the bracket 9^a on the rocking member 9^b, and the groove *m* in the master cam C can be engaged by the pin 11 as hereinbefore described.

The inner trunnion *m'*, of the master cam 115 is preferably provided with an extension (Fig. 5^a) which has a plurality of longitudinally tapered splines 7^e (Fig. 5^a), which are adapted to telescopically engage a corresponding series of grooves 7^e formed in a coupling member 7^b (Fig. 5) on the adjacent end of the shaft 7. This connection makes an absolutely positive drive connection between the shaft 7 and the master cam C. 120

125 The body of the blank B for the actuating

member is preferably truly cylindric as shown (Figs. 8 and 9) and of the proper size and diameter; and the blank has a reduced portion b^2 at each end, and shoulders 5 b (see Figs. 8 and 9) at the junction of the reduced portions with the body; which shoulders are adapted to fit against the thrust bearings; in the gear housing (not shown) when the actuating member is 10 assembled in the gear housing.

Preferrably one reduced end b^2 of the blank is fitted into a socket member 20, (Fig. 9) which has a tapered shank 20^a adapted to engage a tapered recess in the spindle 12^a on 15 the tail stock 12, and the other reduced end b^2 of the blank B is inserted in an opening in a head 21 attached to the spindle 2^a.

The head 21 is provided with a rib 21^a to engage the shoulder b , (Fig. 9) and the end 20 of the head 21 is conical as indicated at 21^b and it is provided with radially disposed series of clamps 22 which pass through radially disposed slots in the head 21, and their ends are adapted to engage the part 25 b^2 of the blank; and their outer ends are beveled and engaged by the beveled inner face 23^c of a flange 23^c on a collar 23 surrounding the head 21 and screwed on the threaded part 21^c of said head, as shown in 30 Fig. 9. Turning the collar 23 in one direction will cause the opposed beveled faces of the flange 23^c and clamps 22 to engage and cause the clamps to positively bite the trunnion b^2 of the blank B and cause it to turn 35 with the spindle 2^a. By turning the collar 23 in the opposite direction the clamps 22 will readily disengage from the blank B. While I prefer to use the means described to cause the blank to turn with the spindle 40 2^a any other suitable means might be employed.

The head 21 is preferably adjustable longitudinally of the head spindle 2^a; being shown as having a shank 21^c non-rotatably 45 fitted into a suitable socket in the end 2^c of the spindle 2^a; and the shank may be adjusted longitudinally of the spindle 2^a and held by means of a nut 2^x mounted on the threaded portion 21^c of the shank and abutting 50 against the end of part 2^c of the spindle 2^a. By having the head 21 adjustable longitudinally of the spindles 2^a and the center 12^a also adjustable, the blank B can be adjusted longitudinally and relative to the axis 55 of the rocking support 9^b, so that the true longitudinal center of the blank will be directly in line with and above the true center on which the rocking support 9^b is mounted.

This means and manner of centering the 60 blank B in the machine insures that the grooves in the actuating member B will be cut uniformly and accurately, and the completed actuating member will fit truly and accurately in the gear casing when assembled 65 therein.

An index segment 9^c (Figs. 1-3—7-10) is attached to the rocker member 9^b adjacent the cutter 10^c, and a pointer 9^t is attached to the frame 8 in fixed operative relation to the index plate. This pointer and index 70 plate show the exact position of the cutter relative to the length of the groove to be cut in the actuating member at any time. When the pointer 9^t points to the center mark "0" on the index plate the cutter would be at or 75 in line with the exact center of the arcuate movement of the cutter. When the rocker member 9^b is shifted to the right or left, the mark in the index plate opposite the pointer will show in what position the cutter 10^c 80 lies relative to the blank during the setting up operation, and show how much of the groove has been cut.

The cutter 10^c is preferably a milling cutter, made of the highest grade of cutting 85 steel, and preferably corresponds exactly in elevation to a cross section of the groove to be cut in the blank B. The blanks for the actuating member are accurately formed and finished except for the helical groove before 90 they are introduced into the machine.

Operation.

When the machine is properly assembled, 95 the master cam C will be in the position described; and the blank is properly positioned as indicated in Figs. 1—2—7—8 and 9. The slide 8 and support 18 are relatively adjusted so that the longitudinal center of the cylindric portion of the blank B or the longitudinal center of the helical groove to be formed in the blank is directly opposite the longitudinal center of the groove m in the master cam C.

The slide 8 is manipulated to retract the 105 cutter 10^c out of the way of the blank B before the latter is placed in position for cutting.

After a blank B is properly positioned and centered between the head and tail stocks 2 and 12, opposite to and parallel with the master cam C as above described, the operator turns the rocker member 9^b to one side until the pin 11 is shown to be in the right position on dial see Fig. 10 or so positioned at one end of the groove in the master cam, as to bring the cutter 10^c directly opposite the portion of the actuating member blank B, wherein the corresponding end of the groove is to be cut.

The cutter spindle 10 is then revolved, but the blank B is held stationary between the centers and the master cam is also held from rotating, while the operator (by manipulating slide 8) advances the cutter 10^c toward the blank B until the cutter has been entered to the proper depth into the blank B.

To facilitate entering of the cutter into the blank a suitable hole might be drilled in 130

the blank before it is placed between the centers. During this operation of seating the cutter in the blank, the blank B is held stationary, and the cam C is also held stationary.

After the cutter has initially entered into the blank B the operator engages the clutch 3^r by means of clutch lever 3^s which controls the rotation of shaft 3, and when shaft 10 3 is rotated the cam C and actuating member blank B are rotated in exact unison. The cutter 10^e is continuously driven at proper speed, during the cutting of the spiral groove in the blank B; and both the 15 master cam C and the blank B are turned very slowly at a pre-determined relative speed; and the combined effect of the rotation of the master cam C, of the actuating member blank B, of the cutter 10^e on its spindle, and of the lateral movement of the cutter 10^e caused by the rocking of the member 9^b (by the pin 11 engaging the groove m in the master cam C) results in cutting a 20 helical groove in the blank B exactly corresponding to the groove in the master cam.

The master cam is so formed that beginning, say, at the left hand end of the groove, the revolving cutter is made to traverse a path from left to right with gradually decreasing rate of movement until it reaches the longitudinal center point of the length of the groove, and from such central point on to the right-hand end of the groove the cutter is made to traverse a path with a 30 gradually accelerated rate of movement; with the result that the longitudinal center of the helical groove cut in the blank has a pitch practically of 90° to the axis of the blank, and the pitch of the groove gradually 35 increases from such center toward each end of the groove, being of highest pitch at the ends of the groove.

What I claim is:

1. In a machine of the character specified, 45 the combination of means for holding and rotating an actuating member blank, a rotatable cutter; means for relatively moving the cutter and blank to cause the cutter to enter or withdraw from the blank; and 50 means including a master cam whereby the cutter is moved at variable speed laterally on an arc extending longitudinally of the blank, during the cutting operation, whereby a spiral groove is cut in the blank.

2. In a machine of the character specified, 55 the combination of means for holding and rotating an actuating member blank, a rotatable cutter; means for relatively moving the cutter and blank to cause the cutter 60 to enter or withdraw from the blank; and a master cam, and means whereby the cutter is moved laterally at variable speed on an arc extending longitudinally of the blank during the cutting operation, whereby a 65 variable spiral groove is cut in the blank.

3. In a machine of the character specified, a master cam, means for holding a master cam, means for holding and rotating an actuating member blank, a rotatable cutter; means for relatively moving the cutter and blank to cause the cutter to enter or withdraw from the blank; and means whereby the cutter is moved laterally on an arc extending longitudinally of the blank during the cutting operation whereby a spiral 75 groove is cut in the blank.

4. In a machine of the character specified, a master cam, means for holding and rotating a master cam, means for holding and rotating an actuating member blank, a rotatable cutter; means for relatively moving the cutter and blank to cause the cutter to enter or withdraw from the blank; and means whereby the cutter is moved laterally on an arc extending longitudinally of the blank, 80 during the cutting operation whereby a variable spiral groove is cut in the blank.

5. In a machine of the character specified, means for holding and rotating a master cam, means for holding and rotating an actuating member blank; a rotatable cutter; a support for said cutter; means for relatively moving the cutter and blank to cause the cutter to enter or withdraw from the blank; means on the support engaging the master cam whereby the cutter is moved laterally on an arc extending longitudinally of the blank, whereby a spiral groove is 95 formed in the blank.

6. In a machine of the character specified, 100 means for holding and rotating a master cam having a variable spiral groove; means for holding and rotating an actuating member blank; a rotatable cutter; a support for said cutter; means for relatively moving the cutter and blank to cause the cutter to enter or withdraw from the blank; means on the support engaging the master cam whereby the cutter is moved laterally and longitudinally of the blank on an arc, whereby a variable spiral groove is formed in the 105 blank.

7. In a machine of the character specified, means for holding and rotating a master cam; means for holding and rotating an actuating member blank; a rotatable cutter; a rocking support for said cutter; means for moving the cutter longitudinally toward or from the blank to cause the cutter to enter or withdraw from the blank, and means on the support engaging the master cam, whereby the support is rocked to move the cutter laterally on an arc extending longitudinally of the blank.

8. In a machine as set forth in claim 7, an indexing plate attached to the rocker support; and a relatively fixed index finger beside said plate, substantially as described.

9. In a machine of the character specified, 125 means for holding and rotating a master

- cam; means for holding and rotating an actuating member blank parallel with the master cam; a rotatable cutter arranged at right angles to the master cam and the blank; a rocking support for said cutter; means for relatively moving the cutter and blank to cause the cutter to enter or withdraw from the blank, and means on the support engaging the master cam, whereby the support is rocked to move the cutter laterally on an arc longitudinally of the blank.
10. In a machine as set forth in claim 9, an indexing plate attached to the rocker support, and a relatively fixed index finger beside the said plate, substantially as described.
11. In a machine of the character specified, means for holding and rotating a master cam having a variable spiral groove; means for holding and rotating an actuating member blank parallel with the master cam; a rotatable cutter arranged at right angles to and between the master cam and the blank; a rocking support for said cutter; means for moving the cutter longitudinally toward or from the blank to cause the cutter to enter or withdraw from the blank; and means on the support engaging the grooved master cam whereby the support is rocked to move the cutter laterally on an arc longitudinally of the blank, whereby a variable spiral groove is formed in the blank.
12. In a machine as set forth in claim 11, an indexing plate attached to the rocker support, and a relatively fixed index finger beside said plate, substantially as described.
13. In a machine of the character specified, means for holding and rotating an actuating member blank, a master cam having trunnions whereby it is supported in position, a driven shaft in axial alignment with the master cam, and a slidale spline and groove connection between one of the trunnions of the master cam and the end of said driven shaft, a rotatable cutter; means for relatively moving the cutter and blank to cause the cutter to enter or withdraw from the blank; and means whereby the cutter is moved laterally longitudinally of the blank during the cutting operation whereby a spiral groove is cut in the blank.
14. In a machine of the character specified, means for holding a master cam, means for holding a cam blank parallel with and adjacent the master cam, a rocking member mounted between the cam and blank, a rotatable cutter mounted in said rocking member and movable therewith, means for rotating the cutter; a shaft for rotating the cam; a rotatable spindle for rotating the blank, a driven shaft, and worm gearing between said driven shaft and the cam driving shaft, and between said driven shaft and said spindle, whereby the spindle and cam may be rotated in unison.
15. In a machine of the character specified, means for holding a master cam; means for holding a cam blank parallel with and adjacent the master cam, a rocking member mounted between the cam and blank, means for adjusting the rocking member longitudinally between the cam and the blank, a rotatable cutter mounted in said rocking member and movable therewith, means for rotating the cutter, a shaft for rotating the master cam, a rotatable spindle for rotating the blank, a driven shaft and worm gearing between said driven shaft and the cam driving shaft and the said spindle, whereby the spindle and cam may be rotated in unison.
16. In a machine of the character specified, means for holding a master cam having a variable spiral groove; means for holding a cam blank parallel with and adjacent the master cam; a rocking member mounted between the cam and blank, means for adjusting the rocking member longitudinally between the cam and the blank; a rotatable cutter mounted in said rocking member and movable therewith; means for rotating the cutter; means on the rocking member engaging the spiral groove in the cam; a rotatable shaft for rotating the master cam; a rotatable spindle for rotating the blank; a driven shaft; and worm gearing between said driven shaft and the cam driving shaft, and between the said driven shaft and the said spindle whereby the spindle and cam may be rotated in unison.

In testimony that I claim the foregoing as my own I affix my signature.

DAVID E. ROSS.
